CASH REGISTER

Walter J. Pasinski, Howell, Mich., assignor to
 Burroughs Adding Machine Company, Detroit,
 Mich., a corporation of Michigan

Application September 15, 1933, Serial No. 689,659

11 Claims. (Cl. 235—14)

This invention relates to cash registers and is more particularly concerned with the operating and controlling means for the totalizing registers therein.

3 It is the general object of this invention to provide an improved cash register construction.

It is a more particular object of this invention to provide a novel operating mechanism for an accumulating register in a cash register.

10 It is a further object of this invention to provide a novel controlling mechanism for an accumulating register in a cash register.

It is also an object of this invention to provide a novel "non-add" control for the accumulating 15 register of a cash register.

Further objects and their resultant advantages will be apparent from the following description given in connection with the drawings in which,—

20 Figure 1 is a right side sectional elevation of a cash register showing the accumulating register and associated mechanisms in normal position;

Fig. 2 is a perspective view of an accumulating register having three sections, one for the units, 25 one for the tens and one for the dollars orders of the machine and showing the operating connections therefor;

Fig. 3 is a right side sectional detail of an accumulating register with certain of the parts cut away and others omitted to illustrate the construction more clearly and showing the register 30 in normal position;

Fig. 4 is a view similar to Fig. 3 and illustrating the register with a unit key of one key section 35 fully depressed;

Fig. 5 is a view similar to Fig. 3, but illustrating the driving connections of the register in non-add position and during the depression of a digit key;

40 Fig. 6 is a partial plan view of the accumulating register with the control connections in non-add condition due to partial depression or preset position of the paid-out key; and

Fig. 7 is a right side sectional elevation showing the paid-out key construction.

Cash register mechanism

The cash register operating mechanisms will not be claimed in this application, being the subject matter of my co-pending application, Serial 50 No. 689,656 filed September 15, 1933, but will be briefly described in order to better comprehend this invention. For a full disclosure of the cash register mechanism reference is made to my 55 above co-pending application.

The cash register mechanism instead of being mounted within a cast frame is mounted and carried between right and left side or end plates 1 which support the entire mechanism and are maintained in spaced relation by tubular members 3 and by various shafts of the cash register mechanism. This construction not only facilitates assembly, inspection, and repair of the machine, but reduces weight and also cost of production. 5

The cash register operating mechanisms include two rows of depressible keys 4 of the necessary denominations and numbers in each denomination. The keys are journaled on a cross shaft 6 secured to end plates 1 and are urged 10 clockwise about shaft 6 by springs 7, the movement of the keys being limited by cross bar 8. Each key has a rearwardly and upwardly extending arm 9 which engages a hollow cross shaft 11 carried at each end by one arm of full stroke 20 lever 12 secured to shaft 6 adjacent each end thereof. The shaft 11 and full stroke levers 12 constitute a universal bail, the rocking movement of which is restricted by means of arcuate slots 13 formed in the side plates and through 25 which the ends of shaft 11 project. Levers 12 which are constantly urged clockwise by springs 14 terminate at their upper ends in full stroke sectors 15 engageable by pawls 17 to insure a full stroke being made each time levers 12 are 30 oscillated.

A key coupler 18 extends across substantially the entire machine, being journaled upon shaft 11 and is provided with a rearwardly and downwardly extending lip 19 adapted to engage lugs 21 35 extending upwardly from each of the key levers. The coupler is urged clockwise by a pair of springs 22 so as to normally urge lip 19 into the path of movement of lugs 21 by means of which all keys may be latched to the coupler and all 40 partially depressed keys or latched keys are carried downwardly upon full depression of any one key.

The upper end of each key lever terminates in a differential cam slot 23, the different slots being 45 of different inclinations. The keys with their slots constitute means for differentially positioning the register 24 as well as the indicator tab magazines 26. The register 24 may be of any desired type and is illustrated as of the type 50 shown in the Horton Patent No. 1,326,504, issued December 30, 1919. There is a register section for each denomination of keys and a pair of indicator tab magazines for each denomination of keys. 55

The keys of each section or denomination of keys through their slots 23 engage a bail 30 extending across the corresponding denomination of key levers and carried by spaced arms 31 journaled on shaft 32. Bail 30 enters the forked end of arm 33 of a crank also journaled on shaft 32 for positioning the tab magazines as described in my co-pending application Serial No. 689,658, filed September 15, 1933, to which reference is made for details of the mechanism involved. The crank also has a second arm 34 projecting downwardly therefrom for indexing the registers as explained in my above copending application. The second arm in normal position also engages a restoring bail 36. Bail 36 extends across the entire width of the machine and is carried by crank arms 37 also journaled on shaft 32. The latter crank arms 37 have an integral arm 38 having a cam groove 39 into which project studs 39^a carried upon upwardly and rearwardly extending arms 12^a of the full stroke levers 12.

From the foregoing it will be apparent that upon depression of keys 4, bail 30 and crank arms 34 are differentially rocked about shaft 32 in accordance with the key depressed to index both the tab magazines and the register and to actuate the restoring bail 36 which serves positively to return magazines 26 to normal position at the completion of each operation or return of each key.

It will be understood that there is a bail 30 and a crank arm 34 for each denomination of keys, that is, one for the dimes, one for the cents and one for the dollars, whereas there is one return bail 36 for all of the keys.

Indexing of register sections

The accumulating register has a corresponding section for each denomination of keys and bails 30. Each section of the accumulating register is connected to its corresponding crank arm 34 by a link 40 having one arm attached to the lower end of crank arm 34 and its other arm attached to one end of a toggle link 41 by a pin 41^a which constitutes the intermediate pivot of the toggle links. The operation and control of each section of the accumulating registers is the same, and therefore, the operation and control of only one section will be described.

The forward end of toggle link 41 is connected to an actuator or rack 42 pivoted at 43 to the accumulator register frame 44, the rack being normally urged clockwise about pivot shaft 43 by a spring 46, and the movement of the rack being limited by a stud 47 projecting through an arcuate slot 48 formed in frame 44. Rack 42 being connected by means of links 41 and 40 to arm 34, is differentially moved a varying distance at each operation of the machine in accordance with the key or keys depressed in its section or denomination.

Rack 42 is in constant mesh with a gear 49 journaled upon a shaft 51 fixed to end frame 44. Gear 49 is fixed to a plate 52 which carries a spring pressed pawl 53 in position to engage spaced lugs or teeth 54 carried by a gear 55. Depression of a key rotates gear 49 through rack 42 which gear rotates pawl 53 clockwise, which upon return stroke of the key and gear turns in a counterclockwise direction, engages a lug 54, and rotates gear 55 counterclockwise. Gear 55 in turn rotates the counter or register wheel 24, in accordance with the key depressed, the latter wheel, of course, having numerals on its periphery as shown in Figs. 2 and 6. In normal or

returned position pawl 53 is always at the top as shown in Fig. 3 so as to engage the uppermost lug 54. It will be understood that the foregoing mechanism is repeated for each register section as previously stated. If a No. 1 digit key is depressed, pawl 53 will upon depression and just prior to return stroke, assume the position shown in Fig. 4, in which it is about to engage a second lug 54^a to rotate gear 55 and register wheel 24 one digit, as shown in Fig. 4.

In order to positively insure pawl 53 of engaging the proper lug 54 it is desirable to move pawl 53 to a point well beyond the lug which it is to engage upon the return stroke, that is, it is desirable to give pawl 53 a "lead" in clockwise rotation over the variable distances it has to move in counterclockwise rotation.

Each link 40, of course, moves varying distances with the arms 34 to which they are attached in accordance with the key of its order which is depressed. Each movement forward and backward is through the distance necessary to move the tab magazine from normal position to its new indexed position. To impart a constant additional movement or lead to the register indexing means or to a portion of the driving connections, link 40 is provided at its forward end with a cam slot 60 slightly arcuate during the major portion of its length and terminating at its forward end in an upwardly inclined portion 61 (Figs. 3 and 4). Cam groove 60 is engaged by a pin 62 carried by a yoke 63 mounted for horizontal sliding movement on shaft 43 for reasons which will later appear.

In normal position pin 62 (Fig. 3) rests in the upper end 61 of the cam groove 60 in which position the toggle link 41 is slightly below horizontal position. Upon depression of any key and resultant forward movement of link 40, pin 62 causes a slight raising of the forward end of link 40 and of the rear end of link 41 to the position shown in Fig. 4. The raising of toggle links 40 and 41 from Fig. 3 position to Fig. 4 position imparts a slight additional forward movement to rack 42 over the movement of link 40 necessary because link 40 is indexed only the exact distance required to position the indicator tabs at each operation of the machine. This additional movement to rack 42 is constant and not cumulative and is a "lead" which insures that the pawl 53 will clear the stud 54 which it is to engage upon return movement as is shown in Fig. 4. In this figure a number 1 key has been depressed and the pawl upon return movement is intended to engage the first lug 54^a clockwise of the upper lug 54 and as can be seen pawl 53 is resting upon the second lug 54^b clockwise of the upper vertical lug 54, thus insuring that it will engage the first lug 54^a upon return or counterclockwise movement of pawl 53.

The major and substantially horizontal portion of the groove 60 is slightly arcuate to compensate for the arcuate movement of arm 34 and insures substantially horizontal movement of toggle link 41 after pin 62 has cleared the upper portion 61 of groove 60.

Non-add control of the register

Occasionally an amount is paid out of the cash register and while it is desirable to have an indication of the amount paid out and, in fact, to enforce an indication being made of the amount given out, the amount so paid out should not be accumulated in the register.

For non-adding or paid-out transactions a special paid-out key 70 is provided. This key is locked to the preset key 71 by means of a locking pawl 72 pivoted to the paid-out key and a stud 73 projecting from the preset key so that it cannot be depressed unless the preset key is depressed. The preset key is connected to the universal bail and the key coupler so as to rock the latter to preset position at which position the 10 coupler is in the path of movement of projections 21 whereby thereafter any keys may be latched to the key coupler. The paid-out key also has a forwardly projecting finger 74 extending forwardly from its rear arm 9 in position to contact the return bail 36 so that the paid-out key cannot be depressed beyond preset position, but inasmuch as the machine must be in preset condition before the paid-out key can be depressed, one or more digit keys must 20 be depressed after depression of the paid-out key to release the machine from preset condition and to indicate the amount withdrawn when the paid-out key is depressed unless, of course, the preset key is depressed again, which will release 25 the paid-out key and leave the machine in preset condition.

The paid-out key is coupled to yoke 63 to disengage pins 62 from cam groove 60 to place the accumulating register in non-adding condition

as will now be explained.

Partial depression of paid-out key 70 causes its lower edge to engage a cam 75 on a lever 76 pivoted intermediate its ends at 77 to a bracket 78 secured to the side frame 1. The upper 35 end of lever 76 is connected to one end of a link 79, the other end of which is connected to a bail 63 and causes it to slide horizontally upon pivot shaft 43. The sliding movement is sufficient to disengage pins 62 from cam grooves 60.

When pins 62 are disengaged from cam grooves 60 and a key is depressed, link 40, of course, moves forwardly, but toggle link 41 instead of moving upwardly or horizontally drops downwardly and the racks 42 being held in clockwise position by springs 43 are not moved upon movement of links 40 and toggle links 41. On the contrary, links 40 and 41 drop downwardly as shown in Fig. 5 and no action whatever takes place in the register.

To positively prevent any upward movement of the links when the paid-out key is depressed, a stud 80 (Fig. 6) is positioned on each of the links 40 and positioned to engage the underside of studs 62 when the latter are disengaged from cam grooves 60. For instance Figs. 5 and 6 show the parts in position during a paid-out or non-add operation, during which the studs 62 are moved sideways out of engagement with the cam slots 60 and 61. Then when a digit key is depressed link 40 is allowed to move downward as seen in Fig. 5 and without moving the actuator rack 42. During the return stroke of the digit key, link 40 is moved upwards under control of lever 41 and unless some means is provided the link 40 may move beyond its normal position to a position where the slot 60-61 will not align with the stud 62 and which would prevent the other studs 62 and the yoke 63 from returning to normal. The use of stud 80 on each link 40 is to prevent an overthrow of the links 40 when returning to normal during a paid-out operation, by limiting against the under side of the studs 62 as shown in Fig. 6, the studs insure the proper alignment of studs 62 and slots 60-61 just as the machine is restoring to normal dur-

ing a paid-out operation. During the other operations when the studs 62 are in constant engagement with slots 60-61 the studs 80 do not perform any active function.

To insure positive return of bail 63 with its 5 studs 62, paid-out key 70 is provided with a bracket 81 which carries a pin 82 in position to engage the underside of cam 75 upon raising of paid-out key 70, thus positively swinging lever 76 clockwise about its pivot as viewed in Fig. 2 10 and returning link 79 and bail 63 to normal or engaged position.

It will be apparent from the foregoing that there has been provided an accumulating register which requires very little energy to operate and 15 which is positively and accurately actuated at each operation of the keys, a "lead" or advance movement being given to positively insure proper engagement of the pawl with the tooth intended to be engaged in the register driving gears. Furthermore, the register may be disabled by a 20 simple breaking of the toggle connection in the drive.

It will also be apparent to those skilled in the art that minor changes may be made in the details of the construction without departing from the spirit and scope of the invention as defined in the appended claims.

What I claim is:

1. In a cash register, depressible keys, an indexing bail differentially moved varying distances by said keys, an accumulating register, operating toggle connections between said bail and said register for indexing the latter in accordance with said keys, and means for varying the position of said toggle connections to control the movement imparted to said connections by said bail.

2. In a cash register, depressible keys, an indexing bail differentially moved varying distances by said keys, an accumulating register, operating toggle connections between said bail and said register normally operative to index the latter in accordance with said keys, and adjustable means operable when in one position to 45 nullify the effect of said toggle connections upon said register.

3. In a cash register, depressible keys, an indexing bail differentially moved varying distances by said keys, an accumulating register, 50 operating toggle connections between said bail and said register for indexing the latter in accordance with said keys, and means acting upon one link of the toggle connection for varying the position of said toggle connection to control the 55 movement imparted by said connections.

4. In a cash register, depressible keys, an indexing bail differentially moved varying distances by said keys, an accumulating register, an actuator therefor, operating toggle links connecting said bail and said register actuator for indexing the latter in accordance with said keys, one of said links having a cam groove therein, and a stud engaging said groove to control the relation of said links to vary the movement of 65 said connections.

5. In a cash register, depressible keys, an indexing bail differentially moved varying distances by said keys, an accumulating register, an actuator therefor, operating toggle links connecting said bail and said register actuator for indexing the latter in accordance with said keys, one of said links having a cam groove therein, a stud engaging said groove to control the relation of said links to vary the movement of said con- 70 75

nections, and means for removing said stud to completely nullify the effect of said connections upon said actuator.

6. In a cash register, depressible keys, an indexing bail differentially moved varying distances by said keys, an accumulating register, an actuator therefor, operating toggle links connecting said bail and said register actuator for indexing the latter in accordance with said keys, means engaging one of said links to control the movement of said links, and means for removing said controlling means to completely nullify the effect of said toggle links upon said actuator.

7. In a cash register, depressible keys, an indexing bail differentially moved varying distances by and in accordance with the key depressed, an accumulating register, operating connections between said bail and said register for indexing the latter in accordance with said depressed keys, and means for controlling said connections to give a constant increment of movement to a portion of said connections in addition to the differential movement given to said connections by said bail.

8. In a cash register, depressible keys, an indexing bail differentially moved varying distances in accordance with the keys depressed, an accumulating register, an actuator therefor, operating toggle connections between said bail and said register actuator, and adjustable means operable to vary the position of the intermediate pivot of said toggle to enable said toggle connections to transmit motion from said bail to said register actuator for indexing the latter in accordance with the keys depressed when said adjustable means is in one position and to nullify the

ability of said toggle connections to transmit motion when in another position.

9. In a cash register, depressible keys, an indexing bail differentially moved varying distances in accordance with the keys depressed, an accumulating register, an actuator therefor, operating toggle connections between said bail and said register actuator for indexing the latter in accordance with the keys depressed, and means for controlling said toggle connections to cause an increase in the movement of said register actuator by a constant amount over the movement given thereto by said bail.

10. In a cash register, depressible keys, an indexing bail differentially moved varying distances by said keys, an accumulating register, an actuator therefor, operating connections between said bail and said register actuator for indexing the latter in accordance with said keys, means for controlling said connections to give a constant increment of movement to a portion of said connections in addition to the variable movement given thereto by said bail, and means for disabling said latter means to nullify the effect of said connections upon said actuator.

11. In a cash register, depressible keys, an indexing bail differentially moved varying distances by said keys, an accumulating register, an actuator therefor, operating toggle connections between said bail and said register actuator for indexing the latter in accordance with said keys, means for varying the position of said toggle connections to increase the movement imparted by said connections, and means for disabling said latter means to nullify the effect of said connections upon said actuator.

WALTER J. PASINSKI.
